WATER TUBE BOILER BAFFLE

Leslie A. Hicks, Honolulu, Territory of Hawaii

Application November 12, 1930
Serial No. 495,029

4 Claims. (Cl. 110—98)

This invention relates to boilers, and more particularly to a special construction of baffles in a water tube boiler characterized by a plurality of tube banks and longitudinal baffles to produce multiple gas passes.

An object of the invention is to provide longitudinal baffles and baffle spacer supports for a tube boiler which provides gas passes in which the gases sweep along and around the tubes adjacent to the baffle.

A further object of the invention is to provide a baffle arrangement in a water tube boiler limiting the corrosion on the gas side of the water tubes.

Other objects will be apparent to those skilled in this particular art from the description in the specification in connection with the attached drawings, in which—

Fig. 1 is a side view of the boiler setting embodying this invention;

Fig. 2 is a detail view of an embodiment of the invention;

Fig. 3 is a sectional view taken along the line 3—3 of Fig. 2;

Fig. 4 is a sectional view taken along the line 4—4 of Fig. 2.

In the embodiment of the invention chosen for purposes of illustration there is shown in Fig. 1 a boiler of the Stirling type, mounted in a conventional boiler setting. Three upper drums 1, 2 and 3 are joined together by steam circulators 4 and 5, and the drums 2 and 3 are further connected by water circulators 6. The drum 1 is connected with a lower drum 7 by means of steam generating tubes 8. The upper drum 2 is connected with the lower drum 7 through steam generating tubes 9 and 10, and the upper drum 3 is connected with the lower drum through the tubes 11, 12 and 13.

Tubes 12 have a baffle 15 mounted thereon in a manner and for a reason to be described in detail later, and the rear row of the bank of tubes 10 has a baffle 20, similar in character to the baffle 15, mounted thereon in a manner to be subsequently described.

In the ordinary baffles known in the art that rest directly upon or against the row of tubes located at the desired baffle points, zones of no gas flow or still pockets are formed between the tubes and baffles. In all boilers the gases of combustion contain some moisture, the percent depending upon the chemical nature of the fuel, the amount of water contained therein, and the amount of moisture in the air used to complete combustion. The greater the ratio of water

vapor to other gases in the products of combustion from a furnace, the greater will be the tendency of the water vapor to condense, and the condensation will start at higher temperature.

When still or dead gas pockets are formed between a baffle and tubes, the temperature of the gases often drops to the dew point at that point, and condensation occurs, even when the temperature of the main stream of gases passing that zone is higher than the dew point.

When the sulphuric anhydride which is present in virtually all gases of combustion, in varying percent depending upon the amount of sulphur contained in the fuel, comes in contact with condensed water on the tubes, sulphuric acid is formed and serious corrosion takes place.

The baffle assemblies 15 and 20 illustrating this invention are made up as shown in detail in Figs. 2 to 4 and include a plurality of refractory blocks 16 placed adjacent each other and resting on spacer bars 17. Pins 18 pass through the spacer bars into certain of the refractory blocks and thus hold the baffle assembly together. The length of the spacer bars will be such that an unequal expansion or contraction thereof with respect to the rest of the baffle assembly will not be sufficiently large to disrupt the assembly.

As shown in Fig. 1 in the baffle assembly 15, the spacer bars 17 thereof rest upon the inclined tubes 12 and the lower end of the assembly rests upon the lower drum 7. This assembly by virtue of the aforesaid arrangement is supported in place but left free to slide along the tubes 12 so that it will not be harmed by any unequal expansion or contraction of parts due to changes in temperature.

In the baffle assembly 20, the spacer bars 17 rest upon the inclined tubes 10 and the lower end of this assembly rests upon an angle bar 21 secured to the lower part of tubes 10. By virtue of this arrangement the assembly is supported in place but is allowed to move along the tubes when expansion or contraction takes place due to temperature changes.

The spacer bars 17 of the two assemblies 15 and 20 rest upon their several tubes and serve to separate the baffle blocks therefrom. By virtue of this separation, the gases of combustion that are deflected by the block construction of the baffle assembly are caused to sweep along and over the tubes, and the formation of any dead gas or still pockets is prevented, with the

subsequent prevention of moisture condensation and its attendant corrosive action.

The baffle arrangement just described insures that the gases of combustion to be baffled will be directed in the desired passes and will sweep the outside of all the tubes at all times during the operation of the boiler. As the gases of combustion will sweep all portions of all the tubes, the formation of any still pockets along 5 the tubes adjacent the baffling will be prevented. Hence, so long as the main stream of the gases of combustion has a temperature above the dew point of the gases, the condensation of water on these tubes, with the subsequent formation 10 of a corrosive agent, will be prevented.

This invention provides an effective baffle arrangement for limiting corrosion on the gas side of water tubes adjacent the baffles, and although a specific arrangement has been shown and described, it is to be understood that changes, substitutions and additions may be made within the spirit of the invention as limited by the appended claims.

What I claim is—

- 25 1. In a boiler characterized by a plurality of tubes and multiple gas passes, baffles determining said gas passes and including a plurality of refractory blocks having adjacent abutting edges, spacer bars disposed between said blocks and certain of said tubes and secured to said blocks proximate the ends of each bar.
- 20 2. In a boiler characterized by a plurality of

tubes and multiple gas passes, baffles determining said gas passes including a plurality of refractory blocks having adjacent abutting edges, spacer bars disposed between said blocks and certain of said tubes, and pins securing the blocks to said bars proximate the end of each bar.

3. In a water tube boiler having a row of vertical tubes, a vertical baffle adapted to expand and contract longitudinally relative to said tubes and comprising horizontal rows of imperforate refractory blocks having abutting edge portions, narrow spacer bars extending transversely of and slidably contacting with said tubes and interposed between said blocks and tubes, and means for holding said bars and blocks in a unitary formation.

4. In a water tube boiler having a row of vertical tubes, a vertical baffle adapted to expand and contract longitudinally relative to said tubes and comprising horizontal rows of imperforate refractory blocks having abutting horizontal edge portions, pin recesses formed in said edge portions, spacer bars extending transversely of and slidably contacting with said tubes and interposed between said blocks and tubes, and pins at horizontally spaced points on said bars fitting said recesses and holding said bars and blocks in a unitary formation.
